(57) **CLAIM**

The ornamental design for the hand spa, as shown and described.

DESCRIPTION

FIG. 1 is a front elevational view of the hand spa showing our new design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view thereof.

The broken line showing of the cord is for illustrative purposes only and forms no part of the claimed design.
